UNITED STATES PATENT OFFICE.

WILLIAM P. DE WITT, OF SOMERVILLE, MASSACHUSETTS.

MOUTHPIECE FOR SALIVA-EJECTING APPARATUS.

1,155,342.

Specification of Letters Patent.

Patented Oct. 5, 1915.

Application filed October 8, 1912. Serial No. 724,672.

To all whom it may concern:

Be it known that I, WILLIAM P. DE WITT, a citizen of the United States, residing at Somerville, in the county of Middlesex and State of Massachusetts, have invented certain new and useful Improvements in Mouthpieces for Saliva-Ejecting Apparatus; and I do hereby declare the following to be a full, clear, and exact description of the invention, such as will enable others skilled in the art to which it appertains to make and use the same.

The present invention relates to saliva ejecting apparatus for use in dental work, and more particularly to a mouth piece for the same.

The object of the present invention is to provide a mouth piece for saliva ejecting apparatus which shall be simple in construction, efficient in operation to drain both the lingual and the buccal portions of the mouth simultaneously, and which shall not interfere with either the vision or the manipulations of the operator.

Another object of the present invention is to provide a mouth piece of the above character which may be adjusted for use in either the right or left portion of the mouth as desired.

Further objects of the present invention are to provide a mouth piece for saliva ejecting apparatus with means for firmly securing the same in position without discomfort to the user or liability of accidental displacement, and also with means for depressing or retracting the lower lip.

With these and other objects in view apparent to those skilled in the art, the present invention consists in the devices and combinations of devices hereinafter described and more particularly defined in the claims.

In the accompanying drawings which illustrate what is now considered the preferred form of the present invention, Figure 1 is a side elevation of the improved mouth piece; Fig. 2 is a top plan view of the same, showing in broken lines the position of certain parts reversed for use upon the opposite side of the mouth from that on which the parts as shown in full lines are designed to be used; Fig. 3 is an enlarged horizontal sectional detail on line $w-w$, Fig. 1, of the pivotal connection of the clamping member; and Fig. 4 is a front elevation of the same; and Fig. 5 is a ver-

tical sectional detail showing the method of adjusting and securing the contact piece upon the clamping lever.

The mouth piece illustrated in the drawings comprises an eduction tube 1 having at its lower end 2 provision for connection to the usual hose or tube through which the saliva is drawn and discharged by some suitable suction device. The upper end of the eduction tube is curved to extend over the teeth of the lower jaw of the user, and to its downwardly turned end 3 is connected a suction tube which consists of the two downwardly bent members 4 and 5 adapted to be positioned upon opposite sides of the teeth so that one drains the lingual and the other the buccal portion of the mouth, through saliva intake openings 6 located adjacent the lowermost portion of these members. These members are connected at their rear ends by a transverse upwardly arched member 7 adapted to extend over the teeth. Preferably, each of the downwardly bent members is provided with an outwardly bowed shield or deflector 8 secured to the outer side of each member which not only prevents the tissues from closing over the saliva intake openings 6, but which also hold the tongue and cheek away from the teeth.

It has been found that if a single eduction tube is to be employed connected to only one of the downwardly bent members through which not only the saliva entering its intake opening but also that entering the intake opening of the other member is exhausted, then the intake opening in the member connected to the eduction tube must be of less area (preferably about one-half), than the cross-sectional area of the suction tube, for otherwise there will be insufficient suction in the other member to render it operative. This feature of single eduction tube and transverse connecting member at the rear of the suction tube is of importance, since it avoids the interference with vision and manipulations of, and the inconvenience to, the operator by the multiplicity of eduction and connection tubes at the front of the mouth, as in the devices of the prior art. Preferably, the eduction tube is offset with relation to the suction tube, as shown in Fig. 2, so that if the suction tube be located in the mouth with the member 4 draining the lingual portion and the member 5 the buccal portion, the eduction

tube 1 will be located at substantially the extreme side of the mouth opposite to that on which the suction tube is located, thus avoiding all possibility of interference with or inconvenience to the operator by the eduction tube.

In the preferred construction as illustrated in the drawings, the mouth piece is adapted for use upon either side of the mouth, the eduction tube and the suction tube being made as separate parts, having provision for connecting the front end of either of the downwardly bent members to the eduction tube. A convenient form of connection is shown in the drawings, in which the down-turned end 3 of the eduction tube is formed with a tapered socket and the members 4 and 5 are formed with correspondingly tapered front ends. Fig. 2 shows in full outline the position of the parts when adjusted for use on the left side of the mouth, the member 4 which then drains the lingual portion of the mouth being connected with the eduction tube. When it is desired to use the mouth piece on the right side of the mouth, the member 4 is disconnected from the eduction tube and the member 5 connected, the suction tube then being brought into the position shown in dotted lines in Fig. 2.

In order to prevent the tapered end of a downwardly bent member from turning in the tapered socket in the eduction tube, the latter is provided with a slot or recess 9 adapted to receive a pin 10 secured in the end of each of the members.

It will be observed that in this preferred construction having provision for the reversing, as it were, of the suction tube, the intake openings 6 should be of equal area in both members, and less than that of the cross-sectional area of the suction tube. Furthermore, it has been found that with these intake openings properly proportioned, both members of the suction tube are properly operative, notwithstanding the open end of the member unconnected with the eduction tube.

In the preferred embodiment of the present invention means are also provided for holding the mouth piece securely in position, and a convenient arrangement for securing this result is shown in the drawings as comprising a contact piece 11 mounted upon a clamping lever 12 pivoted upon the stud 13 near the lower end of the eduction tube and adapted to be secured in adjusted position by the wing clamping nut 14. In order to hold the lever securely in proper position without requiring the application of excessive force to the wing nut, the engaging faces of the plate or boss 15 on the tube 1 and of the end 16 of the clamping lever 12 are beveled or wedge-shaped, as shown in Figs. 3 and 4, the bevels being so

arranged that any downward movement of the contact piece 11 tends to bring the thicker portions of the end 16 opposite the thicker portions of the boss 15, thus forcing the parts into closer contact and enabling them more firmly to resist relative movement. By slightly raising the contact piece 11 and the clamping lever 12, the parts will be loosened so that the wing nut 14 may easily be turned, no matter how tightly the parts had previously been held.

To provide for the adjustment of the contact piece 11, both angularly of the clamping lever 12 and also along the same nearer to or farther from the ejector tube 1, the outer end of the clamping lever 12 is provided with a slot 17 through which passes the clamping screw 18 rigidly secured to the contact piece 11, a wing nut 19 holding the parts in their adjusted position. The angular adjustment of the contact piece 11, it will be noted, is required not only to provide for peculiarities in shape or contour of the jaw of different users, but also to permit the use of the mouth piece upon either side of the mouth.

When operating upon the teeth at or near the front of the mouth, a lip depressor will be found of great convenience to retract or depress the lower lip. Such a device is shown at 20, in Figs. 1 and 2, and comprises a curved rod provided at one end with a split hub 21 encircling the eduction tube 1 and provided with a clamping screw 22 and a wing nut 23. To permit use of the device upon the opposite side of the mouth, the depressor, after first loosening the wing nut 22 and disconnecting the suction tube, may be slipped off the end of the eduction tube and then replaced in reversed position.

The mode of operation of the improved mouth piece is as follows: The proper downwardly bent member of the suction tube having been connected with the eduction tube according to the side of the mouth upon which the mouth piece is to be located, and the lip depressor, if to be used, correspondingly adjusted, the mouth piece is then placed in the mouth with the two downwardly bent members on opposite sides of the teeth. The contact piece is then adjusted beneath the jaw of the user, and the wing nut 14 tightened. The lip depressor is then adjusted to the desired position.

So long as suction is applied to the eduction tube saliva will be drawn from both the buccal and the lingual portions of the mouth as fast as it accumulates, the deflectors 8 at the same time keeping the tongue and cheek away from the teeth and avoiding the moistening of any work which may be being performed.

Having thus described the present invention and shown the preferred embodiment thereof, what is claimed is:

1. A mouth-piece for saliva ejecting apparatus comprising a suction tube having two members, one adapted to drain the lingual, and the other the buccal portion of the mouth and connected at their rear ends, and each provided with a saliva intake opening, one end of the suction tube being free, and a single eduction tube extending from the other end of the suction tube, substantially as described.
2. A mouth piece for saliva ejecting apparatus comprising a suction tube having two members, one adapted to drain the lingual and the other the buccal portion of the mouth and connected at their rear ends, each of said members being provided with a saliva intake opening, and an eduction tube adapted to be connected to the front end of either of the members to adapt the mouth piece for use in either the right or the left side of the mouth, substantially as described.
3. A mouth piece for saliva ejecting apparatus comprising a suction tube having two members, one adapted to drain the lingual and the other the buccal portion of the mouth and each provided with a saliva intake opening, connections between the rear ends of said members, and an eduction tube connected with the front end of one member only and offset in a direction away from the other member, substantially as described.
4. A mouth piece for saliva ejecting apparatus comprising a suction tube adapted to enter the mouth of the user and provided with a saliva intake opening, an eduction tube connected with said suction tube, and means carried by the eduction tube and adapted to be clamped beneath the jaw to hold the mouth piece in position, said means including an angularly adjustable contact piece to adapt the apparatus for use upon either side of the mouth, substantially as described.
5. A mouth piece for saliva ejecting apparatus comprising a suction tube adapted to enter the mouth of a user and provided with a saliva intake opening, an eduction tube connected with the suction tube, a clamp carried by the mouth piece and adapted to engage beneath the jaw to hold the mouth piece in position, and a pivotal connection between the mouth piece and clamp, the engaging faces of said connection being oppositely inclined, substantially as described.
6. A mouth piece for saliva ejecting apparatus comprising an eduction tube, a suction tube connected therewith and adapted to be located in the mouth of a user and provided with a saliva intake opening, means for securing the mouth piece in position, and means carried by the eduction tube for depressing the lower lip of the user, substantially as described.
7. A mouth piece for saliva ejecting apparatus comprising an eduction tube, a suction tube adapted to enter the mouth of a user and provided with a saliva intake opening, means for securing the mouth piece in position, and a reversible lip depressor mounted upon the eduction tube, substantially as described.
